FLAME EXPANDER FOR FUEL OIL
BURNERS

William Hesse, Brooklyn, N. Y.

Application April 17, 1943, Serial No. 483,383

1 Claim. (Cl. 110—97)

This invention relates to an improvement in flame expanders for fuel oil burners.

An object of this invention is to provide a fuel oil furnace which utilizes the gun type of burner with an expanded shield so as to cause the gases from the normal flame to be further ignited and thereby increase the efficiency to a high degree of such furnace.

Another object of this invention is to provide an inexpensive and rugged device which may be added as an accessory to an oil burning furnace.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein—

Figure 1 is a sectional view of the flame expander illustrated in use with a conventional type of oil burner.

Figure 2 is a plan view with the top of the oil burner furnace removed.

Figure 3 is a perspective view of the flame expander per se.

Referring to the drawing, 10 denotes a conventional type of fuel oil furnace provided with the oil burner 11 on it which has the usual gun 12 directed into the furnace from which the flame 13 normally strikes the rear wall 14.

In order to increase the efficiency of the fuel oil burning furnace, the expander 15 is mounted therein which expander comprises a rectangular plate 16 provided with a flange 17 and engaging lip 18.

In order to make the expander sturdy and rugged, reinforcing bars or rods 19, 20 and 21 are suitably secured to the rear portion of the expander to the forward portion of the lip 18.

It will be noted that the expander is placed in the furnace at an angle or incline upwardly

so that as more especially shown in Figure 1 of the drawing the rear portion of the expander rests upon the rear wall of the furnace at 22 and the front portion of the expander is supported by the lip 18 upon the furnace portion 23.

In order to center the flame expander within the interior opposite sides 24 and 25 of the furnace, the expander is provided with a projecting lug 26 and adjustable lug 27 slidably mounted on the lip 18 by means of elongated opening 28 and friction holding pins 29.

In the normal operation of the ignition of the fuel injected by the oil burner the flame therefrom normally strikes the rear wall and as a result 15 the unignited gases further strike the flame expander which prevents said gases from escaping and as a result causing said gases to be further ignited and thereby giving off a tremendously expanded or enlarged total flame.

20 It is to be distinctly understood that this invention is applicable in any shape or form of fuel oil burning furnace which furnace may be round, oval, square and so forth.

It will thus be seen that there is provided a device in which the several objects of this invention are achieved, and which is well adapted to meet the condition of practical use.

As various possible embodiments might be made of the above invention, and as various changes 30 might be made in the embodiment above set forth, it is to be understood that all matter herein set forth is to be interpreted as illustrative and not in a limiting sense.

Having thus described my invention what I 35 claim as new and desire to secure by Letters Patent is:

A flame expander for fuel oil burners, comprising a base plate, a plurality of spaced reinforcing members secured to the rear of said plate, an 40 angular flange extending upwardly from one edge of said plate, a lip projecting outwardly from said flange, and a pair of lugs carried by opposed ends of said lip, one of said lugs being adjustable with respect to said lip.
